UNITED STATES PATENT OFFICE

2,591,374

CONDENSATION RETAINING RECEPTACLE

Charles E. S. Place, Highland Park, Mich.

Application October 19, 1945, Serial No. 623,380

4 Claims. (Cl. 65—13)

1

The present invention relates to a novel construction for liquid containers or devices associated therewith.

The primary object of the present invention consists in the provision of a glass, a bottle, or a coaster adapted for supporting a tumbler embodying a novel and improved construction which serves substantially to eliminate dripping of condensed water from the container when raised from the surface on which it is normally supported.

The present invention contemplates the provision of a capillary groove in the supporting base of the container which will be of sufficient size and shape so as to accumulate the water which would normally drip from the container when raised from a surface.

Particularly in the case of containers used for cold liquids, iced drinks, etc., the formation of condensed moisture on the exterior surface of the container presents a problem which up to the present time has not been satisfactorily solved. This problem is more particularly acute in the summertime when the humidity of the atmosphere is uniformly higher and the consumption of cold and iced drinks is more widespread.

As will be apparent from the following specification when considered in connection with the accompanying drawings, the basic inventive idea herein disclosed is susceptible of use in connection with a wide variety of receptacles of the type normally used for serving cold or iced drinks.

In the drawings,

Figure 1 is a side elevational view of a conventional drinking glass or tumbler having associated therewith a coaster embodying the improvements of the present invention, the coaster being illustrated in section in order to illustrate the improvements of the present invention.

Figure 2 is a bottom plan view of the improved coaster construction shown in Figure 1. *

Figure 3 is a side elevational view of a conventional beverage bottle embodying the improvements of the present invention, the bottom portion thereof being illustrated in section to show the improvements of the present invention.

Figure 4 is a vertical sectional view through a drinking glass embodying the improvements of the present invention.

With more particular reference to the drawings, it will be seen that in all embodiments of the invention, it is contemplated that a capillary groove or channel be provided in the base portion of the receptacle and it has been found that when the glass or bottle is raised from a surface, even

2

a wet surface, the accumulated moisture will accumulate in the capillary groove instead of dripping from the receptacle while in elevated position.

In the construction shown in Figure 1 of the drawings, a conventional drinking glass 1 has associated therewith a coaster or separable base portion 2 which, although detachable from the glass 1, is preferably constructed in such a way as to remain in assembled relation with respect to the glass during use. This coaster is preferably formed with an annular, upwardly extending flange 3 serving to provide a recess into which the base portion of the glass will fit snugly enough to retain the glass and coaster in assembled relation during normal use.

The underside of the coaster 2 comprises mainly a flat, plain surface 4 which may or may not be relieved by a central depression 5. Spaced inwardly from the marginal edge of the bottom of the coaster is formed an annular groove or recess 6 which by means of capillary attraction will serve to accumulate the condensed moisture which would normally drip from the glass when the same was raised from a supporting surface.

While the particular material of which the coaster may be formed does not constitute a part of the present invention, it has been found that particularly superior results can be obtained by forming the coaster by injection molding from any one of a wide variety of well known plastic materials. This form of construction is advantageous because it is not only economical for large scale production, but because it inherently results in an accurate product.

It is of great importance that the intersection of the bottom surface of the coaster with the side walls of the channel 6 provide a precise and sharp corner and, further, that the side walls of the groove 6 be substantially parallel in order to obtain the maximum capillary effect. Injection molded plastics readily lend themselves to such a construction and make possible the provision of an accurate and precise article without the necessity of subsequent finishing operations.

As is seen in Figure 3 of the drawings, a conventional beverage bottle may easily be modified to incorporate the improvements of the present invention. In this embodiment, the bottle 7 is provided with a relatively thick, heavy base portion 8 near the outer edge of which is formed a capillary groove or channel 9 similar in form, construction, and function to the channel 6 described above in connection with the preferred embodiment of the invention.

In Figure 4 is shown a tumbler which may be formed either of glass or plastic material. This tumbler 10 is likewise provided with a relatively heavy, thick bottom wall 11 which has formed therein a capillary groove 12 which serves the same purpose as the capillary grooves or channels 6 and 9 described above.

While the precise dimensions of the channels 6, 9, and 12 are not critical, it has generally been found that most satisfactory results will be obtained if these channels are at least as deep as they are wide and that satisfactory capillary action will be obtained if the width of the channel ranges from one-sixteenth to nearly three-sixteenths of an inch.

Many other and further modifications of the invention falling within the scope thereof, as set forth in the following claims, will become apparent to those skilled in the art.

What is claimed is:

1. A receptacle for iced or cold beverages, said receptacle having side walls and a base portion having formed therein an annular capillary groove, the intersections of the side walls of said groove with the bottom surface of said receptacle forming a relatively sharp corner.
2. A coaster for association with a drinking glass, comprising a cup-shaped, upper portion adapted to receive a drinking glass therein, and a base portion having formed therein an annular capillary groove, the intersections of the side walls of said groove with the bottom surface of said coaster member forming a relatively sharp corner.
3. A drinking glass for iced or cold beverages having walls and a base portion, said base having in its under surface an annular capillary groove, the intersections of the side walls of said groove with the said under surface of said base portion forming a relatively sharp corner.
4. A bottle or similar container for iced or cold

beverages having a base portion formed in its under surface with an annular capillary groove, the intersections of the side walls of said capillary groove with the said under surface of said base portion forming a relatively sharp corner.
